MILo C. DODGE, OF PLYMOUTH, MASSACHUSETTS, ASSIGNOR TO PLYMOUTH CORDAGE COMPANY, OF PLYMOUTH, MASSACHUSETTS, A CORPORATION OF MASSACHUSETTS.

MARKING DEVICE FOR ROPES.

1,282,390.

Specification of Letters Patent. Patented Oct. 22, 1918.

Application filed May 7, 1913. Serial No. 766,035.

To all whom it may concern:

Be it known that I, MILo C. DODGE, a citizen of the United States, residing at Plymouth, in the county of Plymouth and State of Massachusetts, have invented new and useful Improvements in Marking Devices for Ropes, of which the following is a specification.

This invention relates to marking devices for ropes.

Hitherto no satisfactory means has been known, so far as I am aware, for marking the name of the maker, the date or quality or other information upon rope in any permanent fashion. Rope is ordinarily marked by manufacturers with a suitable label on the burlap or other casing which enwraps the coil and by a tag on the burlap or on the coil; but when these have been removed there is nothing to identify the maker with certainty. Efforts in that direction have been made, by making one or more of the strands of a distinctive color, but the number of possible colors is limited; decisions of the courts have made the validity of such a scheme uncertain, when attempted to be used as a trade mark; and the information that can be conveyed by the color of a strand is obviously exceedingly limited. The difficulties arise from the characteristics that are inherent in rope itself; among which are its peculiar shape; the normally uneven character of its exterior surface so that it will not take printing easily or economically; and the wear or abrasion that comes on all parts of its exterior so that anything printed or pasted on the outside is quickly worn off. It is an object of the present invention to provide means by which any desired mark or information can be incorporated permanently in the rope, so that even after a rope thus subject to abrasion has received long and hard usage, the name of the maker, the rated quality, the process by which made, the date or place of manufacture, or any other matter which the maker desires to have preserved may be preserved in connection with the rope so long as the rope itself endures. Inasmuch as it is a characteristic of ropes that they are often cut into pieces, for various purposes and of various lengths that are not known in advance, it is a further object to provide so that this information shall exist in any part of the rope. It is another object to

provide such means in a manner that is capable of use by many different manufacturers simultaneously, or of use for different purposes by the same manufacturer, instead of its possibilities being exhausted when used by one particular maker or when used to signify one particular thing, as in the case of the use of a colored strand.

The objects of the invention are accomplished by combining a peculiar tag, or whatever the marking device be called, with the strands of the rope in a position where it is surrounded and protected by the body and substance of the rope, and yet does not interfere in any respect with the utility of the rope. In form the marker is an attenuated flat strip of material, laid longitudinally through the interior of the rope. Inasmuch as this is not subject to wear, and is not expected to serve the functions of a part of the rope, as are the strands which have hitherto been made of particular colors, it does not need to be of material having any particular strength, and it may be of paper. So constructed it takes up practically no room, adds practically nothing to the cost or weight of the rope, and yet affords a flat and continuous surface on which any desired data may be printed, or which may convey the desired information by its own texture, material, color or other characteristic, or by its mere presence.

An embodiment of the invention is illustrated in the accompanying drawings, in which—

Figure 1 is a side elevation of a portion of rope;

Fig. 2 is a transverse section of the same on the line 2—2 of Fig. 1; and

Fig. 3 shows a portion of the marker.

In the drawings, the numerals 10, 10, 10 indicate the three strands which, when laid or twisted together, make up the rope as a whole. The marker 11 is a flat, thin strip of material which, in the finished rope, lies in the interior of one of the strands. Its position is seen in the transverse section Fig. 2, where it is also seen that this marker is surrounded by the threads 12 that compose the strand. It lies longitudinally of the strand, instead of circling spirally or helically around the strand as the threads 12 do. This is clearly seen at the right in Fig. 1, where several of the threads are represented as being severed and turned up. In the interior

of the strand thus opened, the marker strip 11 is seen extending centrally through the strand 10 in the longitudinal direction of the strand. The difference between the direction of this marker 11 and of the threads 12 that compose the rope is clearly manifest. It is thus protected from abrasion by the influences that wear the threads on the surface of the rope when in use.

10 This marker may be incorporated in the rope at the time of its manufacture by running it into the strand beside or on the surface of the core or central thread 12' of the strand, by machinery similar to that which 15 would be used for running in a central thread. In either case no separate manufacturing operation is required. The introduction of the marker thus adds nothing to the cost of the rope, except the cost of the 20 marker itself. And it may be introduced in this manner into any kind of rope or cordage whether of the specific structure illustrated or otherwise, and whether made with 25 a greater or smaller number of threads per strand, or of strands, and with or without a core, or otherwise.

The structure of the marker itself may 30 vary greatly, but is to be distinguished from those cases where marking is attempted by the coloring of one of the component strands of the rope. The marker now being described is in the nature of an attenuated body introduced into the interior of the rope, protected thereby and having its own 35 peculiar status therein, independently of the material that regularly constitutes the rope. Because of this independence it requires practically no strength in itself. Being collapsible transversely, it can have any desired 40 configuration, the form shown having straight parallel edges. It can conform in shape to the space which it finds available between its surrounding threads. It does not materially affect the exterior form or 45 the correctness of the internal structure of the rope; and it is at the same time capable of carrying on one or both sides any desired printed matter. Such matter may be repeated upon it at short intervals indefinitely.

50 The marker being flat, it will take a good impression of reasonably small size type; and as the surface of the rope marker is protected from wear by the rope structure, the print remains fresh and legible as long as 55 the rope lasts.

While a frail flat surfaced substance such as paper is suggested as a possibility for the material of this marker, thus illustrating that it is not a part of the rope, and is not 60 the same as mere printing upon one of the strands of the rope, nevertheless the invention is not limited to that, and stronger material may be used if desired.

Fig. 3 illustrates the shape which the 65 marker may have, whatever its material, and

further illustrates the structure of a marker, not made of paper but which is considered advantageous. This consists of a number of fine threads 13, laid parallel to each other without interweaving, and held to each other by glue, sizing, or the like. Fifteen or twenty or more of such threads 13, of cotton or any other flexible and inexpensive material may be printed as desired, while thus insecurely fastened together side by side, 75 and then introduced into the rope as a marker as above described. The insecurity of the fastening of the parallel threads 13 to each other enables this tape to split longitudinally when laid in the rope, wherever such splitting happens to accommodate the internal structure of the rope. This carries to a high degree the characteristic above mentioned of non-interference with the correct form and structure of the rope. At 80 the same time whenever a strand containing the marker is unraveled, these originally parallel threads 13 can be brought back into proximity, however much they may have been separated from each other in the strand, 90 and the printing thereon will then be legible. Such a marker adds no appreciable amount to the weight of the rope, and if made of paper it contributes nothing to its strength. Inasmuch, therefore, as it is not relied upon 95 as a strength giving part of the rope the component materials of the marker and their internal structure or arrangement relative to each other, may be varied greatly as may best serve economy or convenience, or as may 100 serve to convey information by mere difference of material or internal structure. If made of the parallel-thread components above described it may or may not contribute some strength, depending on the strength of 105 its threads, but such contribution is only incidental, the marker not being a part of the regular rope structure. The discrepancy in size which may ordinarily exist between it and the regular threads 12 that make up the 110 strands that compose the rope is clearly manifest in Fig. 2, where the marker shows in cross section as a mere short line, while the strand threads are circles of appreciable size.

It will be seen that the rope thus embodying the marker is self-identifying, the marker described being of thin, flat and pliant tape, independent of the strain bearing elements of the rope, extending substantially parallel to them throughout the length of the rope and wholly within its boundaries without displacing them relatively to each other in such manner as to effect either their normal strength or the operation of the 125 whole as a rope.

Under ordinary circumstances the presence of this marker in the rope is not evident, because the marker normally does not come to the surface, and is covered by the 130

rope materials that surround it. Its presence may be discovered at any time, however, and data borne upon it read, by unlaying the rope and untwisting the strand in which it is, either at the end of the rope or elsewhere.

In conducting business as a manufacturer of rope it may be of considerable value to know with certainty the usual behavior, for example, of a particular grade or growth of hemp, or of steel made by a particular formula. Special individual tests can be made of selected ropes, but no method has hitherto been known by which the performance of the general output of such ropes in the hands of consumers throughout the country can be compared with that of other ropes of the same general sort, because of the impossibility of pursuing a large number of individual ropes through the market into the hands of consumers and getting reports thereon. By the aid of the present invention, however, the obtaining of such average results is made possible. A manufacturer who uses the invention to designate in each rope any particular data regarding the ma-

terials of the rope, or the machine or process by which it was made, etc.; can subsequently collect samples of used ropes from customers at large; and by means of the marks preserved therein by the invention can identify them and thus get definite information of results attained under the conditions of actual use. A fund of experience, and of definite knowledge as to behavior of the product, may thus be accumulated which might be a matter of considerable aid to advancement of the industry, or of value in competition with other makers who have not such certain knowledge.

What I claim is:

The combination, with a rope including a core, of means associating information permanently with the rope, comprising a ribbon laid longitudinally through the interior of the rope on the surface of the core.

Signed by me at Boston, Mass., this thirtieth day of April, 1913.

MILO C. DODGE.
